MAURICE D. LARKIN, OF DAYTON, OHIO.

VALVE.

No. 810,951.

Specification of Letters Patent.

Patented Jan. 30, 1906.

Application filed October 15, 1903. Serial No. 177,129.

To all whom it may concern:

Be it known that I, MAURICE D. LARKIN, a citizen of the United States, residing at Dayton, in the county of Montgomery and State of Ohio, have invented a new and useful Improvement in Valves, of which the following is a specification, reference being had to the accompanying drawings, forming part thereof, and in which the same characters of reference designate like parts.

My invention relates to improvements in valves, and more especially to that valve for use under high pressure, such as in connection with fire - hose, fire - engines, hydraulic machinery, &c.; and it consists in the means, constructions, and combinations of the parts hereinafter described, and briefed in each of the appended claims.

In the drawings, Figure 1 is a central vertical sectional view on line X X of Fig. 2. Fig. 2 is a central vertical sectional view on line X X of Fig. 1. Fig. 3 is a plan view of the movable portion of the valve. Fig. 4 is an enlarged plan view of one of the adjusting-nuts. Fig. 5 is an enlarged bottom plan view of the spring member, and Fig. 6 is an enlarged elevation view of the adjusting-screw.

In said drawings, 10 represents the body of the valve, having passage-way 11 therethrough, and across said passage-way is revolvably mounted a cylindrical member 12, having opening 13 therethrough, adapted at times to register with said opening 11. Said member 12 is provided with trunnions 14, projecting from opposite ends and provided with suitable bearings in opposite walls of the valve-casing, and upon the ends of either or both of said trunnions, projecting beyond the valve-body, is mounted a handle or operating-bale 15, by means of which member 12 may be turned, so as to turn on or shut off the flow of water through opening 11 in valve-body 10. The member 12 is of uniform diameter throughout its length, and the cavity in valve-body 10, in which said member 12 is revolvably mounted, is also of uniform diameter and loosely fits the periphery and ends of said member 12.

In the periphery of member 12, at an angle to the opening 13 therethrough, is formed a cylindrical cavity 16, within which is slidably mounted a cylindrical member 17, having on its outer surface a plurality of raised rings 18 and 19, conforming to and closely fitting the curved wall of the cavity within which member 12 is revolvably mounted, the

ring 18 being slightly larger than the diameter of the opening 11 and being adapted to close the mouth of opening 11, leading from the valve-body 10. Said member 17 is prevented from turning in said opening 16 by pins 20, secured at a plurality of points about the edges of cavity 16 and fitting into recesses in the outer surface of said member 17, thus forming a suitable guide for permitting only an outward movement of said member 17 in a radial direction from the longitudinal center of member 12. The under surface of member 17 is provided with a cavity 21, and between the bottom of cavity 16 and the top of cavity 21 is a spring 22, pressed against the bottom of cavity 16 by a screw 23, threaded through said member 17, whereby said member 17 is not only spring-pressed against the curved surface of the cavity in valve-body 10, in which is mounted the member 12, but is adjustable therein by means of said screw 23, to compensate for wear as well as to increase the tension of the spring 22 whenever necessary to prevent leakage, said screw 23 being adjustable by means of a screw-driver introduced through the outlet-opening 11 in valve-body 10, which is surrounded by the threads 25, to which the nozzle is adapted to be secured. It will thus be seen that this adjustment may be simply and readily accomplished without removing any portion of the valve, as well as when the valve is in use, simply by shutting off the water which brings screw 23 centrally into the nozzle end of the opening 11. As shown in Fig. 6, the screw 23 is provided on its lower end with a small portion 26, unprovided with threads, and the lower surface of this portion 26 bears upon the spring 22. This construction prevents the screw 23 from being raised into its threaded opening through member 17 sufficiently to contact with the inner wall of the cavity in valve-body 10, in which member 12 is mounted, and in this respect the ring 19 on member 17, which surrounds said screw-threaded opening for screw 23, indicates to the operator by the relative positions of the head of screw 23 and the outer surface of ring 19 about how much more turning the screw 23 will stand without coming out of its opening and into cavity 16, or about how much more pressure the spring 22 will stand before a new one should be inserted.

In opposite ends of member 12 and surrounding its trunnions 14 is a cylindrical cavity 30, leaving a relatively narrow ring 31

near the periphery of said member 12 at opposite ends. In each of said cavities 30 and surrounding each of said trunnions 14 is a ring 32, of hard rubber or some other suitable material, adapted to bear against the relatively narrow inwardly-projecting ring 33 from the trunnion-bearing and projecting into the cavity of valve-body 10, in which member 12 is mounted. From the outer surface of the opposite ends of valve-body 10 and surrounding said trunnions 14 are screw-threaded openings 40, extending a portion of the way through the walls of said valve-body 10, and each of said openings 40 communicates with a relatively thin cavity 41 of larger diameter in said walls of said valve-body 10. These cavities 41 are for the purpose of rendering somewhat pliable the portions of the valve-body 10, having said rings 33 and the bearings for said trunnions 14, and said pliable portions are acted upon by nuts 42, threaded into said openings and loosely surrounding said trunnions 14, said nuts 42 being adjustable by slots 43 in the outer ends of said nuts for the purpose of causing said rings 33 to bear against the opposite ends of member 12, represented by said rings 32, to compensate for any wear and at the same time to avoid leakage, said rings 32 being placed upon the ends of member 12 to avoid the disintegrating friction between like metals.

By the construction of my apparatus and of the embodiment of the principles of my invention valves are rendered readily and easily operative even under the highest possible pressure, whereas with other constructions they are packed so tight that they are hard to operate even when not under pressure, and when under pressure they must be opened by the application of a long lever or by hammering the short operating-lever with which the valves are conveniently provided.

The preferred form of spring 22 is that of an umbrella-shaped disk of spring metal having a plurality of slots 50 extending from the periphery radially toward the center thereof, the convex side contacting with the screw 23 at its center and the concave side being toward the bottom of cavity 16 in member 12, with the edges of said spring-disk 22 resting upon the bottom of said cavity 16.

The absence of the usual packing necessary with other valves peculiarly adapts this valve for high-pressure service, such as for fire-engines, as well as for use with chemicals of a more or less corrosive nature, in which latter case the different parts of the valve would be made of those well-known substances which best resist the action of such chemicals.

The form of the parts and their construction is such that the manufacturing cost is reduced to the minimum consistent with the highest efficiency, and at the same time the

friction of the valve normally, as well as under pressure, is almost wholly eliminated; but a relatively small friction-surface being provided only at such point or points where leakage is liable to occur, the remaining portions being free from contact with each other, the adjustment for wear being so great that the construction provided by my invention is highly efficient, while other valves of like surface have been worn out and discarded. 70 75

Having now so fully described my invention that others skilled in the art may freely make and use the same when this exclusive grant shall cease to operate, what I claim, and desire to secure by Letters Patent, is— 80

1. In a valve, the combination of a valve-body, having an opening therethrough, a valve member movably mounted in said valve-body, so that said opening may be opened or closed thereby, an operating projection on said member passing through a wall of said valve-body, said wall of said valve-body being formed of a plurality of integral layers with an intervening cavity, and means mounted upon the outer of said layers 90 and adapted to press the inner of said layers against a portion of said member surrounding its operating projection, substantially as specified. 85

2. In a valve, the combination of a valve-body, having an opening therethrough, a valve member movably mounted in said valve-body, so that said opening may be opened or closed thereby, an operating projection on said member passing through a wall of said valve-body, said wall of said valve-body being formed of a plurality of integral layers with an intervening cavity, and a screw threaded into the outer of said layers 100 and adapted to press the inner of said layers 105 against a portion of said member surrounding said operating projection, substantially as specified. 100

3. In a valve, the combination of a valve-body, having an opening therethrough, a valve member removably mounted in said valve-body so that said opening may be opened or closed thereby, an operating projection on said member passing through a wall of said valve-body, said wall of said 110 valve-body being formed of a plurality of integral layers with an intervening cavity, and a hollow screw surrounding said operating projection and threaded through the outer of said layers for pressing the inner of said 115 layers against a portion of said member surrounding said operating projection, substantially as specified. 120

4. In a valve the combination of a valve-body, having an opening therethrough, a valve member removably mounted in said valve-body so that said opening may be opened or closed thereby, an operating projection on said member passing through a wall of said valve-body, said wall of said 130

valve-body being removably secured to said valve-body and formed of a plurality of integral layers with an intervening cavity, and means mounted upon the outer of said layers and adapted to press the inner of said layers against a portion of said member surrounding its operating projection, substantially as specified.

5. In a valve, the combination of a valve-body, having an opening therethrough, a valve member movably mounted in said valve-body so that said opening may be opened or closed thereby, an operating projection on said member passing through a wall of said valve-body, said wall of said valve-body being removably secured to said valve-body and formed of a plurality of integral layers with an intervening cavity, and a screw threaded into the outer of said layers and adapted to press the inner of said layers against a portion of said member surrounding said operating projection, substantially as specified.

6. In a valve, the combination of a valve-body, having an opening therethrough, a valve member movably mounted in said valve-body so that said opening may be opened or closed thereby, an operating projection on said member passing through a wall of said valve-body, said wall of said valve-body being removably secured to said valve-body and formed of a plurality of integral layers with an intervening cavity, and a hollow screw surrounding said operating projection and threaded through the outer of said layers for pressing the inner of said layers against a portion of said member surrounding said operating projection, substantially as specified.

40 7. In a valve, the combination of a valve-body, having an opening therethrough, a valve member movably mounted in said valve-body, so that said opening may be opened or closed thereby, an operating projection on each of the opposite ends of said member and passing through opposite walls of said valve-body, said walls of said valve-body each being formed of a plurality of integral layers with an intervening cavity, and means mounted upon the outer of said layers of each of said walls and adapted to press portions of said member surrounding said operating projection between said inner layers, substantially as specified.

55 8. In a valve, the combination of a valve-body, having an opening therethrough, a valve member movably mounted in said valve-body, so that said opening may be opened or closed thereby, an operating projection on each of the opposite ends of said member and passing through opposite walls of said valve-body, said walls of said valve-body being each formed of a plurality of integral layers with an intervening cavity, and a screw threaded into the outer of said layers

of each of said opposite walls and adapted to press the inner of said layers of each of said walls against a portion of said member surrounding each of said operating projections, substantially as specified.

70 9. In a valve, the combination of a valve-body, having an opening therethrough, a valve member movably mounted in said valve-body so that said opening may be opened or closed thereby, a plurality of operating projections on said member passing through a corresponding plurality of walls of said valve-body, each of said walls of said valve-body being formed of a plurality of integral layers with an intervening cavity, and a hollow screw surrounding each of said operating projections and threaded through the outer layer of each of said walls for pressing the inner of said layers against portions of said member surrounding said operating projections, substantially as specified.

75 10. In a valve, the combination of a valve-body, having an opening therethrough, a valve member movably mounted in said valve-body so that said opening may be opened or closed thereby, a plurality of operating projections on said member and passing through a corresponding plurality of walls of said valve-body, one of said walls of said valve-body being removably secured to said valve-body and each of said walls being formed of a plurality of integral layers with an intervening cavity, and means mounted upon the outer layer of each of said walls and adapted to press the inner layer of each of said walls against portions of said member surrounding said operating projections, substantially as specified.

80 11. In a valve, the combination of a valve-body, having an opening therethrough, a valve member movably mounted in said valve-body so that said opening may be opened or closed thereby, a plurality of operating projections on said member passing through a corresponding plurality of walls of said valve-body, one of said walls of said valve-body being removably secured to said valve-body and each of said plurality of walls being formed of a plurality of integral layers with an intervening cavity, and a screw 85 threaded into the outer layer of each of said walls and adapted to press the inner layer of each of said walls against portions of said member surrounding said operating projections, substantially as specified.

90 12. In a valve, the combination of a valve-body, having an opening therethrough, a valve member movably mounted in said valve-body so that said opening may be opened or closed thereby, a plurality of operating projections on said member passing through a corresponding plurality of walls of said valve-body, one of said walls of said valve-body being removably secured to said valve-body and each of said plurality of walls

walls being formed of a plurality of integral layers with an intervening cavity, and a hollow screw surrounding each of said operating projections and threaded through the outer layer of each of said walls for pressing the inner layer of each of said walls against portions of said member surrounding each of said operating projections, substantially as specified.

10 13. In a valve, the combination of a valve-body having inlet and outlet openings and a cavity intermediate said openings; a valve member revolubly mounted in said cavity and having a stem; a cylindrical recess in one side of said valve member; a cylindrical member 17 slidably mounted on a guide in said recess of said valve member; a spring exerting outward pressure upon said member 17; and means independent of said stem and 20 passing through said member 17 and being accessible through either of said openings for varying the tension of said spring; and an opening 13 through said valve member at angle to the said axis of said valve member, substantially as specified.

14. In a valve, the combination with a valve-body, having openings therethrough communicating with a cavity, a member 12 in said cavity and having trunnions 14 provided with bearings in the walls of said valve-body, an opening 13 through said member 12, a cylindrical cavity 16 in one side of member 12 and remote from the opposite ends of said member 12, a cylindrical member 17 slidably mounted upon guides 20 in said cavity 16, a relatively narrow rib 18 upon the outer surface and near the periphery of member 17, said rib 18 being adapted to engage a portion of the inner wall of said cavity in said valve-body and to close the outlet of one of the openings through said valve-body at times, said cavity 16 and member 17 with its rib 18 being slightly larger in diameter than said first-mentioned openings, and 40 manually-adjustable means passing through said member 17 and accessible through either one of the openings through said valve-body, whereby said member 17 is pressed outwardly, substantially as specified.

15. In a valve, the combination of a valve-body having ways therethrough upon opposite sides of a cavity therein; a member 12 movably mounted across said way and filling said cavity and having a recess in one side thereof; a guide in said recess; a member 17 movably mounted in said recess and slidably upon said guide; said recess and member 17 being relatively smaller than the length of said valve-body, and said member 17 being 50 adapted to close one of said ways through said valve-body; and means exposed upon

the outer surface of said member 17 and accessible through the way closed by said member 17, whereby the relative positions of said members 12 and 17 may be adjusted to 65 compensate for variations in manufacture and for wear, substantially as specified.

16. In a valve, the combination of a valve-body having ways therethrough upon opposite sides of a cavity therein; a member 12 70 movably mounted across said way and filling said cavity and having a recess in one side thereof; a guide in said recess; a member 17 movably mounted in said recess and slidably mounted upon said guide; said recess and 75 member 17 being relatively smaller than the length of said valve-body, and said member 17 being adapted to close one of said ways through said valve-body; and a screw threaded through said member 17 and having its 80 head end exposed upon but below the outer surface of said member 17, said head end of said screw being accessible through the way closed by said member 17, whereby the relative positions of said members 12 and 17 85 may be adjusted by said screw to compensate for variations in manufacture and for wear, substantially as specified.

17. In a valve, the combination of a valve-body having ways therethrough upon opposite sides of a cavity therein; a member 12 90 movably mounted across said ways and filling said cavity and having a circular recess in one side thereof; a guide in said recess; a circular member 17 movably mounted in said 95 recess and slidably upon said guide; a spring member 22 confined in said recess by said member 17; said recess and member 17 being relatively smaller in diameter than the length of said valve-body, and said member 17 being 100 adapted to close one of said ways through said valve-body; and a screw threaded through said member 17 and bearing at its inner end upon said spring member 22 and having its head end exposed upon but below 105 the outer surface of said member 17, said head end of said screw being accessible through the way closed by said member 17, whereby the relative positions of said members 12 and 17 110 may be adjusted manually by said screw to compensate for variations in manufacture and automatically by said spring member 22 to compensate for wear; substantially as specified.

In testimony whereof I have signed my 115 name to this specification, in the presence of two subscribing witnesses, at Dayton, Ohio, this 21st day of May, 1903.
